Application May 31, 1947, Serial No. 751,501

3 Claims. (Cl. 91—12)

1

This invention relates to a machine for applying a band of adhesive to the lasting margins of the uppers of tennis shoes. Such shoes are frequently called sneakers and their uppers are usually called "tops." As herein illustrated, the machine is designed to employ an adhesive having the fluidity of latex.

In shoes of the tennis type which commonly have rubber soles combined with canvas tops it is desired to apply a band of cement along the lasting margin at the bottom of the uppers or tops. The cement is used for lasting the upper over the insole and machines for this purpose must meet a peculiar set of conditions found in this type of work. For example, where the vamps or the tips are joined to the quarters there is usually a seam on each side of the shoe forming a distinct shoulder and the latex must be applied not only to the parts of the work leading up to and following the shoulder but also in the corner at the bottom of the shoulder so that there may be no break in the band. Furthermore, such shoes are provided with a canvas pocket, stitched to the inner side of the top near the heel end, which is referred to as a "junior." This is so stitched to the fabric of the top that its lower edge is spaced from the edge of the top a short distance which is less than the width of the band of cement which it is desired to apply. A machine for this purpose must, therefore, be designed to apply cement along two different levels at this portion of the shoe. Obviously too there are shoulders which are met as the machine meets and leaves the junior.

Accordingly, an object of the invention is to provide an improved cementing machine for this type of work which will feed the work smoothly and will apply a uniform band of cement throughout the whole periphery.

To this end a feature of the invention resides in the provision of a substantially unyielding, driven, work-supporting roll combined with a flexible nozzle and a readily yieldable upper feed roll. As illustrated the nozzle is of the multi-finger or articulated type which is well suited to the application of a band of cement on parts at different levels and in which the individual fingers are pivoted about an axis which lies to the rear of their point of contact with the work so that they swing forwardly and upwardly in encountering changes in thickness. A special mounting is provided for the upper feed roll which is in the form of a disk disposed to engage the work inside the band of cement. This mounting includes a swinging support permitting

bodily movement of the axis of the feed roll, about a pivot for the support which is to the rear of the point of contact between the roll and the work so that the latter swings forwardly and upwardly, as does the nozzle, and the drive mechanism for the roll is such that a gear train is provided in which there is no interference with the swinging movement of the feed roll and in which a driving connection is continually maintained.

These and other features of the invention will best be understood from a consideration of the following specification taken in connection with the accompanying drawings in which

15 Fig. 1 is a front elevation with a portion of the casing removed;

Fig. 2 is an end elevation of the working elements of the machine with parts in section;

Fig. 3 is an angular view of the feed mechanism showing especially the upwardly yieldable mounting for the upper feed roll;

Fig. 4 is a view of a fragment of a piece of a tennis shoe top illustrating a band of cement applied to a portion of a junior; and

Fig. 5 is a rear elevation showing the relation of the nozzle tips to the feed mechanism.

In one typical example, a band of cement is to be applied to the inner lower marginal portion of a top T of a tennis shoe and this top is turned inside out before it is presented to the machine to deposit a band B of cement along one margin (see Fig. 4). At the heel end of the shoe a counter-like piece or junior J is secured to the inside of the top T by stitching and commonly the seam between them is covered with a piece of tape t. The cement band overlaps this junior.

As it is presented to the machine, the work is supported upon a lower feed roll 10 mounted at the end of a shaft 12 and held against a shoulder 14 thereon by a retaining screw 16. The work is guided by engagement with an edge gage 18 to be later described and is gripped against the lower roll by a disk-like upper feed roll 20 carried at the end of a shaft 22 which is journaled in a tiltable carrier block 24 mounted upon a rod 26. This rod extends through a downwardly projecting portion 28 of a bracket 30 (Fig. 1). This bracket 30, for simplicity in setting up the machine, is integral with a rod 32 (Fig. 5) which passes through a boss 34 formed upon the casing or frame 36 of the machine and the rod is held in the desired position by a clamp screw 38 bearing upon a flattened portion of the rod.

A similar boss 40 opposite the boss 34 is secured to the inner side of the frame 36 and to

gether they provide a bearing for a drive shaft 42, the inner end of which passes through the other side of the frame and has a large gear 44 (Fig. 1) meshing with a pinion 46 on a power driven shaft 48.

The drive for the upper feed roll includes a pinion 50 on the outer end of the shaft 42 and meshing with one portion of an elongated pinion 52 (Fig. 3) which is free to rotate on the rod 26 carried by the bracket portion 28. This elongated pinion 52 is in mesh also with a pinion 54 which is secured to the inner end of the shaft 22 carrying the upper feed roll 20 and inasmuch as the center of tilting of the feed roll block 24 is the same as the axis of the elongated pinion 52 there is no hindrance to the tilting movement of that block about its axis and the drive is never interrupted regardless of the position of the upper feed roll.

It will be noted that the bracket 30 is extended outward to provide an abutment 56 between which and the block 24 there is provided a coil spring 58 (Fig. 2) urging the block 24 and hence the upper feed roll 20 downwardly against the work. The limit of downward movement of the feed roll is determined by a stop screw 60 threaded in the block 24 at the rear side of the rod 26 and positioned to engage the underside of the abutment 56. The position of the shaft 22 axially in the block 24 (Figs. 3 and 5) is determined by an enlargement 62 which abuts the outer end of the block and by the engagement of the hub of the pinion 54 with the other end of this block after that pinion has been pinned to the shaft 22.

The shaft 12 for the lower feed roll 10 is journaled in a tilttable carrier 64 (Fig. 1), the inner end of which is forked to provide arms 66 which are pivoted in the front and rear sides of the casing 36 (see Fig. 2) on pins 68 and 70. The shaft 12 is driven by gears 72 and 74 connecting it to the drive shaft 42. This tilting of the carrier 64 allows the lower feed roll to drop between periods of use to facilitate the presentation of a piece of work and, after the work has been brought into engagement with the gage 18, the carrier and the lower roll 10 are raised by means of a lever 76 (Fig. 1) pivoted on the frame on a pin 77. One end of said lever has a forwardly extending arm 78 (Fig. 2) underlying the carrier 64, and the other end has a rearwardly extending portion 80 surrounding a treadle rod 82 on which there is a spring 84 interposed between a collar 86 pinned to the rod and a washer which lies on the arm 80. This tilting movement of the carrier 64 upwardly is limited by a stop screw 88 engaging a shoulder 90 on the frame 36 and when the treadle rod is fully depressed the strength of the spring 84 is such that the lower feed roll 10 is rigidly held in position in so far as any downward pressure of the work is concerned. In other words the spring 84 is several times as effective at the work gripping point as is the spring 58 which urges the upper feed roll 20 downwardly.

The gage 18 is mounted on the carrier 64 by an arm 92 fitting in a groove 94 and adjustably held in position close to the inner end of the feed wheel 10 by screws 95. The gage has a curved portion 97 which slightly overlaps the roll 10 to facilitate feeding the work to the operating point. The carrier 64 also serves as a support for a rod 96 carrying a scraper 98 which may be tilted to be brought into close engagement with the lower roll 10 and then held in adjusted posi-

tion by tightening a set screw 100. The scraper is designed to remove any cement which has accidentally been transferred to the lower roll as for instance when the toe portion of the work piece is scalloped as it sometimes is.

The application of cement to the upper side of a piece of work is effected by means of a multifinger articulated nozzle 102 comprised of a plurality of individual fingers 103 (Fig. 5), pivoted on a pin 104 which traverses the fingers, and is supported in a forked block 106. This nozzle is constructed as illustrated in Letters Patent of the United States No. 2,177,666 patented October 31, 1939, upon the application of 15 W. L. MacKenzie et al. The forked block is secured by screws to a plate 108 having a dovetail bar 109 (Fig. 1) slidably engaging a correspondingly shaped notch in a bracket 110 in which it is adjustably held in position by a set screw 112 (Fig. 2). The bracket 110 has an inwardly extending rod 114 which is received in a cylindrical holder 116 attached by screws 118 to the outer side of the frame 36 and this holder is provided with a split clamp 120 (Fig. 1) arranged to 20 grip the rod when compressed by a clamp screw 122. This provides for setting up adjustment so that the lower work-engaging tips of the nozzle fingers may be positioned substantially above the top of the supporting roll 10. Individual wire springs 124 (Fig. 2) are provided for the successive fingers and the cement is delivered to passages at the lower ends of these fingers through small tubes 126. As in the patented construction these tubes communicate with a chamber in 25 a removable plate 128, the chamber communicating with a passage 130 leading to a passage 132 in a diaphragm valve 133 which enables the supply of cement to be turned off and on at will.

The diaphragm valve 133, illustrated best in 30 Figs. 1 and 2, comprises a cup-like casing 135 at the center of which there is formed a valve seat 134 and to which cement is supplied through a pipe 136 joined by a flexible hose 138 to a supply container not herein shown but which may be 35 of the type shown in Letters Patent of the United States No. 2,110,157, granted March 8, 1938, upon the application of B. Jorgensen. From this receptacle the latex is forced out by compressed air which may be supplied by a compressor 140 (Fig. 40) having a gear connection 142 to the drive shaft 42. Cooperating with the relatively sharp edge of the valve seat 134 is a spring pressed 45 conical pin 144 forming part of a mechanism which is supported in a cap 146 having a bayonet joint connection 148 with the cup portion 135 of the valve 133. A thumb screw 150 is provided to prevent accidental disconnection of the two parts of the valve. In the cap 146 there is a 50 diaphragm 152 held in position by a ring 154 which is recessed to receive a packing to enable a tight connection between the two parts of the valve. The stem of the conical valve point 144 is extended upwardly through the cap 146 and provided with a collar 156 beneath which there 55 is located the forked arm 158 of a two arm lever 160 which is pivoted in a bracket supported by a ring 161 held on a neck of the cap 146. The other arm 162 of this lever 160 extends downwardly for engagement by a roller 164 in the end 60 of an operating lever 166 which is mounted on a cross rod 168 journaled in the frame and having an arm 170 connected to the treadle rod 82 so that it may be turned when the treadle is depressed.

75 In the operation of the machine the operator

will take a piece of work such as that which is illustrated in Fig. 4 and bring its edge into contact with the gage 18. He will then depress the treadle rod 82 to raise the lower feed roll 10 and the work and to open the valve 133. As has been noted, the lower feed roll 10 is held rigidly in position and any yielding required by changes in the thickness of the work is taken up in the upward and forward swinging movement of both the upper feed roll 20 and the fingers of the nozzle 102. The direction of rotation of the feed rolls is indicated by arrows in Fig. 3 and is such that any shoulders or other changes in thickness which encounter the upper feed roll tend to push that feed roll upwardly and forwardly in the direction of movement of the work and thus will offer a minimum hindrance to the easy and even feeding of the work through the machine. This swinging movement of the upper feed roll 20 will be against the tension of the spring 58 and when the work is removed from the machine the extent of downward movement of that feed roll is limited by the stop screw 60 in the bearing block 24. Similarly the fingers of the nozzle 102 will be swung forwardly and upwardly about their pivot pin 104. Some of these fingers will ride along the margin of the top which lies below the junior J while the remaining fingers will be deflected upwardly so that the delivery ends thereof ride up over the junior. This enables the easy feeding of the work through the machine without interference by the nozzle and insures the application of a uniform band B of cement thereto.

Having thus described my invention, what I claim as new and desire to secure by Letters Patent of the United States is:

1. In a cementing machine, coacting feed rolls gripping opposite faces of a piece of work, driving gears connected to at least one of said rolls to feed the work forwardly in a predetermined direction, a carrier block in which one of said rolls is journaled, a support in which said block is movably mounted restricting bodily yielding movement of the feed roll to directions having components forwardly with the work and toward and away from the work, and a flexible nozzle

for applying a uniform band of cement to the upper surface of the work along its margin.

2. In a machine for applying a band of cement to a piece of sheet material movable forwardly in a substantially horizontal plane, work-gripping feed rolls disposed on axes substantially parallel to one another and to the plane of the sheet material gripped between them, a driving mechanism for rotating at least one of said rolls to feed the work, a journal block for one roll tiltable about an axis rearward of the axis of the roll and farther away from the level of the work than is the axis of the roll, and a flexible nozzle having pivoted delivery members inclined downwardly and forwardly, the delivery ends of which rest upon the work adjacent to the tiltable feed roll.

3. In a machine for applying a band of cement to a shoe part movable forwardly in a substantially horizontal plane, an upper feed roll disk, a nozzle for delivering a band of cement to the work beside said disk, said nozzle comprising pivoted delivery members inclined downwardly and forwardly toward the work, a work-supporting feed roll, treadle means for raising said latter feed roll to grip the work against the upper feed roll disk, and a yieldable carrier block in which said upper feed roll disk is journaled, said carrier block being pivoted about an axis parallel to the axis of said feed roll disk, said pivot axis lying to the rear of and above the axis of the feed roll disk, a screw cooperating with said carrier block for determining the lowermost position of said disk, and a spring acting upon the carrier block to urge the feed roll disk toward the work.

HARRY PHILLIPS.
